WEB ROLL CONTROLLING MECHANISM

Charles S. Caffrey, Port Washington, N. Y., assignor to Wood Newspaper Machinery Corporation, Plainfield, N. J., a corporation of Virginia

Application May 17, 1940, Serial No. 335,855

12 Claims. (Cl. 242—75)

This invention relates to web roll controlling mechanisms.

In certain kinds of web treatment, and particularly in processing paper stock, it is necessary to maintain a relatively heavy tension on both the unwinding and winding ends of the travelling paper web while portions of the web intermediate these ends are being operated upon at work stations, such as in calender machines. This tension is particularly great at the unwinding end of the web where the tension may be as much as the web will withstand without rupture. Under such conditions there is a great loss of power under present practice, and it is a difficult problem to maintain a constant tension on both ends of the web at the same time when the intermediate portion is being subjected to a calendering operation.

One of the objects of the present invention is to produce a better finished roll by automatically maintaining a constant winding tension throughout the roll as it increases in diameter.

Another object of the present invention is to unwind a roll by automatically maintaining a constant web tension throughout the unwinding period of the roll.

A further feature of the present invention provides a construction that allows the operation of the machine almost continuously by materially reducing the time lost in removing the wound roll and replacing it with an empty roll, it being only necessary for the machine to be stopped for a short time necessary to make the splice in the web.

A still further advantage in the construction of the present invention resides in the elimination of roll spindle shafts and using chucks instead.

Another feature of this invention is saving in power. On the unwinding end the power customarily wasted in retarding the unwinding roll is translated through the variable speed drive and its chain drives, back into the machine. On the winding end there is a constant slip, and therefore power loss of 10 per cent from the beginning of the wind to the finished roll, whereas the loss, when winding with a conventional slip belt, increases rapidly as the roll increases in diameter, starting at 10 per cent, and terminating in a slip approaching 100 per cent where a large diameter roll is wound on a small core.

It may be found that a uniformly wrapped roll does not prove satisfactory under certain conditions such as severe changes in temperature or humidity. A roll that is wrapped tightly at the core and more loosely toward the circumference

would allow for contraction or expansion without any appreciable change in the paper roll diameter. It is an additional feature of the present invention to provide mechanism whereby the degree of the tightness of the wrap may be regulated throughout the thickness of the roll.

With the foregoing and other objects in view, the invention is set forth in the accompanying specification and illustrated in the drawings for the purpose of teaching its application, but it is to be understood the changes, variations and modifications may be resorted to without departing from the scope of the invention defined by the claims hereunto appended.

15 In the drawings, wherein the preferred form of the invention is illustrated:

Figure 1 is a more or less diagrammatic arrangement of the entire assembly in the nature of a side elevation showing the general arrangement of the three-arm reel, control and drive units, and the calender stack of the present invention.

20 Figure 2 is a fragmentary plan view thereof partly in section showing the arrangement between the drive units.

Figure 3 is a diagrammatic view of the position of a three-arm reel with one roll unwinding, one roll winding, and a third full roll to be processed on one of the reel arms ready to replace the roll being unwound when the same is spent.

25 Figure 4 is a view similar to Figure 3, with the web severed from the rolls after completion of unwinding and winding.

Figure 5 is a view similar to Figure 4 with the 30 reel arms rotated 120° from the position shown in Figure 4, showing the fully wound processed roll preparatory to unloading, the recently unwound core in the winding position with the end of the web anchored thereto, and having the replacement roll in unwinding position having its web spliced to the web passing to the calender apparatus.

Figure 6 is a view similar to Figure 5, showing the completed wound processed roll being removed from the reel arm in preparation to loading a full unprocessed roll on the empty arm while the unwinding and winding rolls are in operation.

Figure 7 is an enlarged end view of one of the 35 transmission drive units removed from the assembly showing a fragmentary portion of the mechanism for regulating the transfer of torque to control the web tension.

Figure 8 is a view similar to Figure 2 illustrating a modified form of mechanism for transferring ring torque by the use of a belt and a tension ap-

plying device, together with the control therefor. Figure 9 is an elevation of one of the torque transferring mechanisms, tension applying device, the control therefor, combined with the speed changing transmission drive unit, all of which are removed from the machine.

Figure 10 is a fragmentary plan view of the reel partly broken away and removed from the assembly illustrating the manner of mounting the rolls on the reel arms.

Figure 11 is a view similar to Figure 10 illustrating a modified form of the invention for mounting the rolls on the reel arms.

Figure 12 is a fragmentary end elevation of the reel shown in Figure 11 of the drawings.

Figs. 13 and 14 are sectional views of the variable speed drive gearing contained in the two driving units.

With these foregoing objects in mind, the arrangement to be described below is designed to produce proper tension control on both unwinding and winding rolls and will save power losses. The customary means of furnishing tension on the unwinding roll is through the use of friction elements, such as friction brakes, and the like, working directly upon the roll or upon the roll shaft. It is, therefore, evident that the loss in power at this point is great. The winding end tension is controlled by slip clutches which attempt to operate the roll faster than web speed will allow.

The means to be employed to control the paper rolls in the present invention, is a variable speed drive unit connected to each roll, which is in turn regulated by a differential control unit. This type of drive may be adapted to various conditions; that is, it may be used on paper roll stands or two or three-arm reels. In the description to follow a three-arm reel installation will be discussed because of certain advantages it has over roll stands or two-arm reels.

Referring to the drawings in detail 9 indicates a reel stand in which a shaft 10 is journaled for selective rotation. The reel 11 is fixed to the shaft 10 and rotates with the shaft. As illustrated in the drawings, the invention may be applied to a reel having three arms 11a spaced approximately 120° apart. In order to rotate the reel a relatively large wormwheel gear 90 is fixed to shaft 10 outside of the stand 9. This gear meshes with a worm gear 91 driven by an electric motor 92 mounted on stand 9 through gears 93, 94 and shaft 95. As indicated in Figure 1, reel 11 is held in fixed position by pawl 96 which engages a notch 97, one on the end of each reel arm 11a. The pawl 96 rocks with a pin 98 journaled on the stand. A handle 99 fixed to the outer end of pin 98 when operated to the right causes the release of the pawl from the engaged position in Figure 1 and frees the reel so that it may be rotated.

To prevent any damage to the machine by premature motor operation, cam switch 100 is located in such a manner that the electric circuit, composed of conductors 101, 102, 103, and switch 100, for the motor, will be interrupted when the pawl operating handle 99 is in locked position, and said circuit will be closed when the handle is in the unlocked position. It will thus be seen that the reel will be automatically rotated to working positions hereafter explained, where it is locked in fixed relation while one roll is unwinding, another is being wound, and a third roll that has been processed is removed and replaced by a mill roll all of which will appear later.

Rolls 12, 13 and 14 are rotatably mounted at the extremities of arms on the reel 11 spaced 120° from one another. A paper web 15, in the instance illustrated, from roll 12 has an intermediate portion thereof passing through the rolls of the calender stand 16 and then is wound on roll 13. In Figure 1, the roll 14 is an unprocessed or mill roll, and has been mounted in the arm of the reel 11 to replace roll 12 when the latter is completely unwound, as shown in Figure 5.

By referring to Figures 3, 4, 5 and 6, the manner of reel operation will be readily understood. Fig. 3 is similar to Fig. 1 in showing the position of the various rolls. In Fig. 4 the roll 12 seen in Fig. 3 has been unwound, leaving core 12a, and roll 13 seen in Fig. 3 becomes fully wound roll 13a. At this point the calender machine is stopped and web 15 is severed from core 12a and roll 13a. Drive clutches to be discussed later are disconnected, and the pawls that lock the reel are released, thereby allowing the reel 11 to be moved automatically through 120° as shown in Fig. 5. When the reel has been moved to the new position locking pawls, to be described, are again engaged, and in doing so, the reel is automatically stopped as will appear later. Referring to Figure 5 roll 14 has now assumed the position previously held by roll 12, and core 12a moves to the position held by roll 13. The ends of the web from the calender stack are then attached to the new roll 14 and core 12a, the variable speed drives are reset, and the drive clutches are connected in. The calender is then started, unwinding roll 14 and winding on the core 12a.

In Figure 6 the advantages of a three-arm reel will be noted. Roll 13a, which has recently been processed, is being removed from the reel by means of a loading jack 18. This may be accomplished without interfering with operations of the unwinding and winding rolls, thereby saving valuable time. With a two-arm reel it would be necessary to remove the freshly processed roll before a mill roll would be inserted.

Referring to Fig. 2, it will be noted that rolls 12 and 13 are carried in the reel arms and connected to speed changing transmission drive units 23 and 27 by clutches indicated generally at 21, 25, respectively.

The rolls 12 and 13, are in working position in Fig. 1 of the drawings. The spindle of roll 12 is connected by means of a clutch 21 to the output shaft 22 of the variable speed transmission drive unit 23 which in the present form is of the Reeves type. In such transmissions an edge-active belt connects adjustable V-shaped pulleys on the input and output shafts 24 and 22, respectively, similar to the Reeves transmission shown in the patent to Perry, 2,168,071, August 1, 1939. The gearing contained in units 27 and 52 is identical with the gearing contained in units 23 and 51. This gearing is shown in Figs. 13 and 14. In Fig. 13, which shows the variable speed driving mechanisms contained in unit 27, is shown shafts 26, 28, 61 and 61a which correspond to the parts bearing the same numerals in Fig. 2. These shafts are mounted in suitable bearings attached to the casing of drive unit 27. Tapered cones 132 and 133 are splined to shaft 26 and cones 134 and 135 are splined to shaft 28. Belt 136 with tapered sides operates on these cones. Levers 137 and 138 are pivoted on pins 139 and 140 respectively, which pins are secured to the casing of drive unit 27. By suitable connections such as trunnions (not shown) levers 137 and 138 may

be used to slide cones 132 and 133 endwise on shaft 26 and cones 134 and 135 endwise on shaft 28 while still permitting the cones to rotate with their respective shafts. It is apparent that when one pair of cones is moved close together the other pair will be moved farther apart, and vice versa. Thus the tapered belt 136 will rise on one pair of cones and fall on the other, changing the effective diameters on which it operates. This mechanism can be used for varying the speed ratio between shafts 28 and 26 as described herein. Control of this variable ratio is accomplished through shaft 61a which has right and left hand threads engaging poppets 141 and 142 which are oscillatably secured to levers 137 and 138 respectively. It is apparent that rotation of shaft 61a in one direction will swing levers 137 and 138 together at one end and rotation of shaft 61a in the opposite direction will swing the levers apart at that same end. Rotation of shaft 61a to give the desired control is derived, through safety clutch 143, from shaft 61 as will be described later.

Regulator shaft 63 is rotatably mounted in the casing of drive unit 27 and has arm 64 secured to its outside end and worm gear 144 secured to its inside end, said worm gear 144 meshing with threads or teeth on shaft 61a so that when shaft 61a rotates worm gear 144 will be moved to oscillate shaft 63. This motion of shaft 63 may be used to control the tightness of the wound roll as described hereinafter.

The shafts 57, 61 and 53 (see Fig. 2) are rotatably mounted by suitable bearings in the casing of control unit 52 and provided with means for preventing end motion. Shaft 61 has secured to it a central member 145 on which bevel gears 146 and 147 are rotatably mounted meshing with bevel gears 148 and 149 which are rotatably mounted on shaft 61. Bevel gear 148 has secured to it a spur gear 150 which meshes with a similar spur gear 151 secured to shaft 53. Bevel gear 149 has secured to it a sprocket 152 which through chain 153 is chained to sprocket 154 secured to shaft 57. Thus it is apparent that bevel gear 148 will be turned in proportion to the speed of shaft 53 and bevel gear 149 in proportion to the speed of shaft 57. If bevel gears 148 and 149 run in opposite directions at the same speed central member 145 and therefore shaft 61 will remain stationary. Any difference in the speeds of bevel gears 148 and 149 will cause shaft 61 to rotate and control variable speed drive unit 27 as set forth hereinafter. Roll 13 is connected in a like manner by clutch 25 to output shaft 26 of the variable speed transmission drive unit 27 like the unit 23 for the roll 12. The input shaft on unit 27 is indicated at 28. It is possible to disengage the clutches 21 and 25 to allow the reel 11 and the rolls to revolve to other work stations, as previously described, bringing the proper roll spindle into alignment, and then engage the clutches with the output shafts 22 and 26, respectively, which drive the respective rolls 12 and 13.

The drive for units 23 and 27 is from pulley 31, the latter being driven by the calender rolls on stand 16, by a chain or belt 32 to the pulley 33 on the main drive, or jack shaft 34. The jack shaft 34 has mounted thereon the sprockets 35, 36, and this jack shaft is also connected to auxiliary drive shaft 37 by a clutch 38, which clutch allows the drive units 23, 27 to be operated independently of the influence of the main drive through the differential control units to be presently described. Shaft 37 is connected to the in-

put shaft 28 of the transmission drive unit 27 for roll 13, by a slip clutch coupling indicated generally at 40 which can be regulated by a lever, to presently appear, to produce a predetermined degree of torque between drive shaft 37 and the input shaft 28. This coupling consists of a male frusto-conical element 41 splined for axial movement on shaft 37, coaxing with a female element 42 in the shape of a cup having a cavity 43 confronting the male element designed to produce the desired torque transfer which in turn controls the web tension. The female element 42 is fixed to input shaft 28. Chain sprocket 44 fixed to shaft 37, is connected by chain 45 and sprocket 46, provided with a handle 39, to auxiliary drive shaft 47, which latter has a torque transfer coupling 48, 41a and 41b alike in all respects to elements 41, 42, and 43 of coupling 40. The coupling 48 connects shaft 47 with input shaft 24 of the transmission drive unit 23 which drives roll 12. It will then be obvious that with these couplings 40 and 48 controlling the transfer of torque, the shaft 37 may be driven faster than roll 13 to produce a tightly wound roll; and on unwinding roll 12, the shaft 47 may be driven slower than the roll 12 to hold the unwinding web under proper tension.

As the unwinding and winding rolls continue to operate, these rolls vary in diameter at the peripheral surface, and, therefore must vary in rotating speed to maintain a constant web speed. Since shafts 37 and 47 are connected to the calender stack drive, they and their respective couplings 40 and 48 will operate at fixed speed. The variable drive units 23 and 27 will allow for roll speed changes. As the unwinding roll 12 becomes smaller, the peripheral surface speed tends to increase, and since the web tension must remain constant, the variable drive units 23 and 27 must be accordingly adjusted. To accomplish this adjustment a control unit operating on a regulation differential gear principle is introduced into the assembly. An application of the differential gear principle as a control unit is illustrated in the patent to Perry, heretofore indicated. A control unit of this character for the unwinding roll 12 is indicated at 51, and the control unit for winding roll 13 is indicated at 52.

The control units 51 and 52 compensate for the difference in speed of the main drive shaft 34 and the speed of the spindles or shaft speeds of the unwinding and winding rolls 12, 13, respectively, and these controls adjust the speed of the drive units. Control unit 52 has its shaft 53 connected by sprocket 54 and chain 55 to the main drive shaft 34 by sprocket 36. Thus shaft 53 forms the constant speed side of the differential control unit 52, and is connected to the main drive shaft 34 at all times. The opposite side of the differential control unit 52, the variable side, is the shaft 57, which is connected by sprocket 58 and chain 59 to sprocket 60 on the input shaft 28 of the drive unit 27. The reactance shaft 61, of the differential control unit, that is, the shaft that operates under the influence of difference in speed of constant shaft 53 and variable speed shaft 28, is connected directly to the speed adjusting shaft 61a of the transmission drive unit 27. This reactance shaft 61 in the differential control unit causes the adjustment in the drive unit 27 of the ratio of the speed between input shaft 28 and the output shaft 26 which latter drives the winding roll 13. Under operating conditions, reactance shaft 61 attempts to reach a

neutral position caused by the difference in speed of shafts 53 and 28. In finding the neutral position, the shaft 61 will rotate adjusting shaft 61a and thereby change the adjustment in the drive unit 27 which is designed in such a manner that the resulting angular speed of the paper roll 13 and the main drive shaft 34 will become adjusted to the correct ratio for any diameter of the paper roll.

The web speed being constant, the diameter of the roll 13 increases as it winds up with the resultant progressive decrease in revolutions per minute as it continues to operate. The decrease in speed slows down shaft 28, causing a greater slip in the torque transfer coupling 40, which coupling runs at constant speed. When shaft 28 slows down it immediately produces a change in the shaft 57 of the differential control unit thereby altering the position of reactance shaft 61 that causes the readjustment of the ratio of the speed, between input shaft 28 and output shaft 26 on the transmission drive unit 27, to the requirement of the moment. This changing of adjustment continues until the roll is wound to full size at which time the machine is shut down and the fully processed roll is moved to the unloading station in the orbit of the reel.

As roll 13 has been decreasing in rotational speed during the winding, the unwinding roll 12 has been increasing in rotational speed because the web speed must remain constant so that it will pass through the calender stack without breaking. In order to produce an increase in the rotational speed of the unwinding roll 12 the control unit 51 has its constant shaft 53a connected to the main drive shaft 34 by chain 55a and sprocket 35. The variable shaft 57a of differential control unit 51 is connected to input shaft 24 by the chain 59a; while reactance shaft 61b has direct connection with adjusting shaft 61c which changes the speed ratio between input shaft 24 and output shaft 22 on drive unit 23 for the unwinding roll. Thus it will be seen that this organization of elements connect control unit 51 with main drive shaft 34, and also connect control unit 51 and drive unit 23, and the speed ratio adjustment of drive unit 23, all of them corresponding to the elements heretofore described in connection with the operation of winding roll 13, and it is believed that more details of the description are unnecessary in view of their clear disclosure in Fig. 2.

It is evident that at this point where the rolls and cores are replaced variable speed drive units 23 and 27 are set to the position opposite that which is necessary for starting the machines with proper web control. At this position a new unwinding roll would flood the paper into the calender while the winding core could not take up the slack fast enough. It is, therefore, necessary to reset the drive units. For the purpose of description, a manual resetting will be described, although a simple motor connection could be used for this purpose. With the machine stopped, clutches 38, 21 and 25 are disengaged. By rotating handle 39 drive units 23 and 27, also shafts 57 and 57a of differential units 51 and 52, will now be rotated, but shafts 53 and 53a of the differential units will not rotate being still chained to shaft 34 which is stationary. With one member of each differential unit stationary and one rotating, the third member of the differential, namely shafts 61 and 61b, connected to the ratio change screws of the variable speed drive units 23 and 27, will rotate to cause their ratios to

change. Handle 39 is rotated manually only long enough to effect total ratio change. When this is done clutches 38, 21 and 25 may be engaged and the drives are set for the next winding and unwinding operation.

Slip clutches 40 and 48 are set for transferring a predetermined constant value of torque between the auxiliary drive and the rolls. When all conditions are ideal, the amount of torque transferred 10 and the variation of the driving units 23 and 27 should produce a roll which is wrapped uniformly for its entire diameter.

It may be found that a uniformly wrapped roll does not prove satisfactory under certain 15 conditions such as under severe changes in temperature or humidity. A roll that is wrapped tightly at the core and more loosely toward the outside would allow for expansion or contraction without any appreciable change in the paper roll 20 diameter. Regulation of the tightness of the wrap can be controlled by a suitable linkage arrangement connected to the speed indicator shaft 63 as shown in Figures 2 and 7. Lever 64 on shaft 63 is connected to male coupling 41 by 25 link indicated generally at 65. As the speed varies, indicator lever 64 will move carrying with it link 65, thereby changing the adjustment in coupling 40 to automatically control slippage, which in turn determines the tightness of the 30 wrap. The indicator shaft 63 is geared (not shown) to shaft 61a, that is a continuation of reactance shaft 61, which changes the ratio of speed between the input and output shafts 28 and 26 on the drive unit 27. It is evident that a 35 means is now available to regulate the paper tension both for an unwinding roll and a winding roll at all roll diameters and that the degree of tightness in the wrap may be also regulated.

Upon further study of Fig. 1, another important 40 feature of this arrangement is evident. As web 15 is drawn through the calender stack 16, it is assisting in operating drive unit 23 which through connections with the main drive shaft 34 is attempting to retard the roll 12. Drive units 45 23 and 27 are connected as previously described, thereby causing web 15 to also operate winding roll drive unit 27. In theory, therefore, it would not be necessary to have any drive for the winding and unwinding mechanism. Friction losses 50 in the units, however, require that drive chain 32 from the calender stack 16 be used. It is now standard practice in the trade to hold tension on the unwinding roll 12 by applying a friction brake of some character to the spindle of the 55 unwinding roll, and this practice wastes all the power in the braking friction. With the present invention this power customarily dissipated is not lost, but all of it, minus the small loss in gearing and slip in the torque transfer coupling 40 is conserved and is pumped back to help wind the winding roll 13.

In Figures 8 and 9 there is illustrated a modification of elements in the assembly, which elements provide for the substitution of a belt and 60 idler pulley to control the transfer of torque between the drive shaft 37 and input shaft 26 of drive unit 27 for the winding roll 13. Like the automatic slippage to control the tightness of the wrap as depicted in Figure 2 of the drawings 65 a drum pulley 73 is fixed on the auxiliary drive shaft 37, and a like pulley 74 is fixed to the input shaft 28 of the drive unit 27 with a flat belt 75 trained over the pulleys. This arrangement is used instead of the coupling 40 in Fig. 2 of the drawings. To regulate the tightness of the wrap 70

and automatically adjust the tension on belt 75 to permit slip between shaft 37 and shaft 28, an arm 78 is mounted to rock on a pivot 79 fixed at a convenient place (not shown) on the machine. An idler pulley 80 is journaled on the end of arm 78 and is pressed against the belt 75. In order to automatically regulate the pressure on pulley 80 to control the wrap, in this form of the invention, the speed indicator arm 64 on indicator shaft 63 has a link 81 connecting it to one branch of a rockable bell crank lever 82. The other branch of lever 82 has a link connection 83 with arm 78 (Fig. 9). As the speed indicator arm 64 on drive unit 27 fluctuates with the alteration of the speed ratio in this drive unit 27, as heretofore explained, the fluctuations are translated through the linkage 81, 82, 83, and idler 80 to belt 75 thereby automatically altering slip between shaft 37 and 28 and producing variation in the tightness of the wrap on winding roll 13. It will be understood throughout this specification that slip or slippage between shafts alters the amount, or degree, or value of the torque transferred from one shaft to the other.

When the reel 11 is moved from one working position to another, it is necessary to provide a quick detachable connection at the clutches 21 and 25 in Figs. 2 and 8 to accomplish this end. In Figs. 10 and 11, an arrangement of mechanical details for accomplishing this detachability is illustrated. Referring to the clutch 21, in Figs. 10 and 11, an operating lever 106 has one end pivoted at 107, to a boss 108 carried by the adjacent transmission drive unit 23 for the winding roll. A pin 109 fixed to an intermediate portion of lever 106 slides in a circular peripheral groove 110 in the rear end of the sliding clutch collar 111 which is slidably mounted on the output shaft 22 of drive unit 23. The lever 106 in the clutch 25 in Figs. 10 and 11 is constructed exactly like the lever for clutch 21, and performs the same function, except the lever is connected to the drive unit 27, and the male clutch collar slides on the output shaft 26.

The sliding clutch collar 111 in Fig. 10 of the drawings, engages with the fixed clutch collar 112 fixed to the outer ends of the roll spindles 113 journaled in the bearings 114, one on the end of each reel arm 11a. In Fig. 11 of the drawings the fixed clutch collar 115 is fixed to the ends of the roll drive shafts 116. It will be obvious in referring to Figs. 10 and 11 of the drawings, that movement of lever 106 to the left, in Figs. 10 and 11, will move the sliding clutch collars 111 respectively, out of meshing engagement with fixed collars 112 on spindle 113 (Figure 10), and fixed clutch collars 115 on roll drive shafts 116 (Fig. 11). Movement of levers 106 in the opposite direction, or to the right, will bring the sliding clutch collars into meshing engagement, respectively, with the fixed collars on the spindles 113 and shafts 116, in which position they are shown in Figs. 10 and 11.

In Figs. 10 and 11, the elements of promoting ease and despatch of mounting and demounting the rolls are shown. In the form of the invention shown in Fig. 10, the spindles 113 journaled in the bearings 114 in the ends of the arms 11a on one side of the reel are formed with tapered chucks 117 which extend into and grip the confronting ends of the tubular core sleeves 118 on which the rolls of web are wound and unwound, when the cores and rolls are assembled on the reel. The arms 11a on the opposite side of the reel have threaded openings 119 on the ends of

the arms which receive a threaded spindle 120, one for each arm. On the outer ends of these spindles are hand wheels 121 by which they are turned into and out of engagement with the ends 5 of the core sleeve 118. On the inner ends of each of the spindles 120, is a tapered head or chuck 122 which is journaled for rotation on the spindles so it will rotate with the rolls while the spindle remains stationary. The chucks 122, grip 10 the ends of core sleeve 118 on the inside, when in the engaged relation, as shown in the upper portion of Fig. 10, and when the spindles are backed off, as shown in the lower portion of Fig. 10, they move free of the core sleeve. It will then 15 be seen that when the clutch collars 111-112 are engaged, and the chucks 117-122 are in gripping relation with the core sleeves 118, the rolls 12, 13 will be driven by the respective input and output shafts 22-26.

To accommodate the character of spindle 116 shown in Fig. 11 of the drawings, the ends of the arms 11a on each side of the reel are provided with sectional bearings in which the cap portions 123 thereof are pivoted at 124 to the 20 bottom portion 125. The bottom portions is integral with the ends of the arms 11a as seen in Fig. 12. On the side opposite the pivot 124, the cap portions are formed with an extension 126. The extension is provided with an enlarged opening 126a which receives a locking bolt 127. These locking bolts have their inner ends pivoted at 12 to the bottom portions 125 of the bearings so as to permit the bolt to rock while the bolt is being trained into and out of the opening 126a to 30 engaged and disengaged positions to hold the cap portions 123 respectively in closed and released position. On the outer free end of the bolts 127 is threaded a wing nut 129 which locks against the extensions 127 on the cap portions 123 of the 35 bearings. The nuts are removed from the bolts, and the cap portions 123 are swung to open position on the pivots for the purpose of bodily removing propelling shafts 116 and the rolls carried thereby.

In order to grip the roll core sleeves 118 and 40 propel the rolls, each of the shafts 116 has a pair of adapters 130, 131, one adjacent each end, leaving free portions of the shaft to be journaled in the bearings on the ends of the arms. The 45 adapters 130, 131 are secured to the shafts 116 and they engage the ends of the core sleeve 118. When clutch collar 115 on the shaft 116 which carries the roll to be demounted, is disengaged from clutch collar 111, the reel may be rotated 50 to a suitable position for removal of the roll. At this position, lock nut 129 is unscrewed, cap 123 is opened and shaft 116, the roll carried thereby, the clutch collar 115, and adapters 130, 131 are removed as a unit. Adapter 131 is then removed 55 from shaft 114 and the shaft is slid out of the roll core sleeve 118 ready to be inserted in an empty core sleeve 118 to be placed back in the 60 bearings from which it was removed.

A means for the automatic regulation of the 65 tightness of the wrap on the winding roll 13 has been heretofore described. In one form of the invention shown in Fig. 2, linkage 64 and 65 moves the male member 41 on the auxiliary drive shaft 37 in response to the change in the speed ratio between the input and output shafts of the 70 transmission drive unit 27. The movement of the male member 41 changes the degree of torque transferred to the female member 42. In the form of the invention in Figs. 8 and 9, the pressure on pulley 80 bearing on belt 75, is automatically regulated by linkage 64, 82, and 83 in 75 re-

sponse to the change in the speed ratio between the input and output shafts of the transmission drive unit 27. The pressure on the belt 75 determines the torque transferred from auxiliary drive shaft 37 to the input shaft 28. This automatic regulation of the torque transferred serves to regulate the tightness of the wrap on the winding roll 13, but is not necessary on the unwinding roll 12.

However, in addition to the mechanism to produce automatic regulation of the torque transmitted from the drive shaft 37, to the input shaft 28, it is sometimes necessary to change or alter the constant value of the torque transferred from shaft 37 to shaft 28. In other words, the automatic regulation may be effective within certain limits, and it sometimes becomes necessary to change the limits. To effect the change in the constant value of the torque transfer from shaft 37 to shaft 28, in the form of the invention in Figs. 8 and 9 of the drawings, the link 83 is parted and the ends are threaded to receive a hand wheel 135 operating on the principle of a turnbuckle, and has a sleeve 136 with right and left hand threads at the opposite ends respectively. The threads on the sleeve engage like threads adjacent the part in the link 83, and when the hand wheel 135 is rotated in one direction greater pressure is applied to belt 75, and the constant torque value is increased. When wheel 135 is rotated in the opposite direction pressure is released on belt 75 and the constant torque value is diminished. A hand wheel 137 alike in construction and function to wheel 135 is applied to link 65 in the form of the invention shown in Fig. 2 of the drawings. It follows that the constant value of the torque at the coupling or clutch 49 in Fig. 2 of the drawings may be altered in addition to the automatic regulation. Thus the constant value of torque transfer between shafts 37 and 28 for the winding rolls 13 is effective in both forms of the invention in Fig. 2 and Figs. 8 and 9.

It is also the aim of the present invention to effect the constant value of the torque transferred from shaft 47 to shaft 24 of the unwinding rolls 12 in both forms of the invention. Since male element 41a is splined at 41b, on shaft 47 for movement relative to the fixed female element this movement to any predetermined position will alter the constant value of the torque transferred between the elements in that form of the invention. To change the constant value of the torque transferred by the belt 72 to the shafts 47 and 24, in Fig. 8, arm 77 may be moved from one position to another on its pivot 77a. In doing so greater or lesser pressure will be applied to belt 72 with the result that greater or lesser degrees of torque will be imparted to the shafts 47, and 24, and thus the constant value of the torque transfer will be effected.

Having thus described my invention, what I claim as new and desire to secure by Letters Patent of the United States is:

1. In a device of the class described comprising an unwinding roll; a winding roll; a driving means for the unwinding and winding rolls; a main power drive; a drive unit for each roll including coacting shafts, one of which is an input shaft, another of which is an output shaft, and a third of which adjusts the ratio of speed between the other two shafts; a differential control unit for each drive unit including coacting elements, one of which is a variably acting element connected with the input shaft of each of the cor-

responding drive units, another of which is a constantly acting element each of which is connected with the main power drive, and another of which is an element actuated by the differential speed of the other two elements and connected with the third shaft of each of the corresponding drive units; a detachable driving connection between the drive means of each roll and the output shaft of each of the corresponding drive units; a driving connection between each of the input shafts of the drive units and the main power drive; and a device in the last-mentioned driving connection for each of the input shafts to provide a predetermined torque transfer between the main power drive and the input shafts.

2. In a device of the class described comprising an unwinding roll; a winding roll; a driving means for the unwinding and winding rolls; a main power drive; a drive unit for each roll including coacting shafts, one of which is an input shaft, another of which is an output shaft, and a third of which adjusts the ratio of speed between the other two shafts; a differential control unit for each drive unit including coacting elements, one of which is the variably acting element connected with the input shaft of each of the corresponding drive units, another of which is a constantly acting element each of which is connected with the main power drive, and another of which is an element actuated by the differential speed of the other two elements and connected with the third shaft of each of the corresponding drive units; a detachable driving connection between the drive means of each roll and the output shaft of each of the corresponding drive units; a driving connection between each of the input shafts of the drive units and the main power drive; and a device in the last-mentioned driving connection for each of the input shafts to provide a predetermined torque transfer between the main power drive and the input shafts.

3. In a device of the class described comprising an unwinding roll; a winding roll; a driving means for the unwinding and winding rolls; a main power drive; a drive unit for each roll including coacting shafts, one of which is an input shaft, another of which is an output shaft, and a third of which adjusts the ratio of speed between the other two shafts; a differential control unit for each drive unit including coacting elements, one of which is a variably acting element connected with the input shaft of each of the corresponding drive units, another of which is a constantly acting element each of which is connected with the main power drive, and another of which is an element actuated by the differential speed of the other two elements and connected with the third shaft of each of the corresponding drive units; a driving connection between the drive means of each roll and the output shaft of each of the corresponding drive units; a driving connection between each of the input shafts of the drive units and the main power drive; and a device in the last-mentioned driving connection for each of the input shafts to provide a predetermined torque transfer between the main power drive and the input shafts, and means actuated by the third shaft of the drive unit for the winding roll only and connected with the corresponding one of said devices adapted for automatically regulating the tightness of a roll of web wrapped on the winding roll.

4. In a device of the class described comprising an unwinding roll; a winding roll; a driving means for the unwinding and winding rolls; a main power drive; a drive unit for each roll including coacting shafts, one of which is an input shaft, another of which is an output shaft, and a third of which adjusts the ratio of speed between the other two shafts; a differential control unit for each drive unit including coacting elements, one of which is a variably acting element connected with the input shaft of each of the corresponding drive units, another of which is a constantly acting element each of which is connected with the main power drive, and another of which is an element actuated by the differential speed of the other two elements and connected with the third shaft of each of the corresponding drive units; a driving connection between the drive means of each roll and the output shaft of each of the corresponding drive units; a driving connection between each of the input shafts of the drive units and the main power drive; and a device in the last-mentioned driving connection for each of the output shafts to provide a predetermined torque transfer between the main power drive and the input shafts; and detachable means in the driving connection between the drive means of each roll and the output shaft of each drive

unit to permit removal of the rolls without disturbing the position of the output shafts.

4. In a device of the class described comprising an unwinding roll; a winding roll; a driving means for the unwinding and winding rolls; a main power drive; a drive unit for each roll including coacting shafts, one of which is an input shaft, another of which is an output shaft, and a third of which adjusts the ratio of speed between the other two shafts; a differential control unit for each drive unit including coacting elements, one of which is a variably acting element connected with the input shaft of each of the corresponding drive units, another of which is a constantly acting element each of which is connected with the main power drive, and another of which is an element actuated by the differential speed of the other two elements and connected with the third shaft of each of the corresponding drive units; a detachable driving connection between the drive means of each roll and the output shaft of each of the corresponding drive units; a driving connection between each of the input shafts of the drive units and the main power drive; and means connected with the last mentioned driving connection and actuated by the third shaft of the drive unit only for the winding roll adapted for automatically regulating the tightness of a roll of web wrapped on the winding roll.

5. In a device of the class described comprising an unwinding roll; a winding roll; a driving means for the unwinding and winding rolls; a main power drive; a drive unit for each roll including coacting shafts, one of which is an input shaft, another of which is an output shaft, and a third of which adjusts the ratio of speed between the other two shafts; a differential control unit for each drive unit including coacting elements, one of which is a variably acting element connected with the input shaft of each of the corresponding drive units, another of which is a constantly acting element each of which is connected with the main power drive, and another of which is an element actuated by the differential speed of the other two elements and connected with the third shaft of each of the corresponding drive units; a driving connection between the drive means of each roll and the output shaft of each of the corresponding drive units; a driving connection between each of the input shafts of the drive units and the main power drive; means connected with the last mentioned driving connection and actuated by the third shaft of the drive unit only for the winding roll adapted for automatically regulating the tightness of a roll of web wrapped on the winding roll; and detachable means in the driving connection between the drive means of each roll and the output shaft of each drive unit to permit removal of the rolls without disturbing the position of the output shafts.

6. A device of the class described comprising a supporting stand; a reel mounted on the stand to revolve periodically to predetermined working positions and there to remain fixed for a certain period; a pair of rolls journalled on the reel in spaced relation to each other; a work station; a continuous web adapted for winding on one roll as it is unwound from the other roll and having a portion intermediate the rolls operated on under constant tension at the work station; a driving means on each roll; a main power drive; means connected with the driving means, one for each roll, for varying the rotational speed of

the driving means for the rolls; a member connecting each of the last mentioned means and the main driving means; each of said members including coacting elements providing slippage between the rotational speed varying means and the main power drive; and means including a differential speed driving means connected to the main power drive and each of the rotational speed varying means arranged to control the rotational speed varying means.

7. A device of the class described comprising a supporting stand; a reel mounted on the stand to revolve periodically to predetermined working positions and there to remain fixed for a certain period; a pair of rolls journalled on the reel in spaced relation to each other; a work station; a continuous web adapted for winding on one roll as it is unwound from the other roll and having a portion intermediate the rolls operated on under constant tension at the work station; a driving means on each roll; a main power drive; means connected with the driving means, one for each roll, for varying the rotational speed of the driving means for the rolls, means including a differential speed driving means connected to the main power drive and each of the rotational speed varying means and actuated by said differential speed driving means whereby to compensate for the variance in the rotational speed in the driving means; a female member having a cavity and connected with each of the rotational speed varying means; and male members on the power drive each having a portion thereof conforming in shape to the cavity and coacting with a female member to provide slippage between the rotational speed varying means and the power drive.

8. A device of the class described comprising a supporting stand; a reel mounted on the stand to revolve periodically to predetermined working positions and there to remain fixed for a certain period; a pair of rolls journalled on the reel in spaced relation to each other, a work station; a continuous web adapted for winding on one roll as it is unwound from the other roll and having a portion intermediate the rolls operated on under constant tension at the work station; a driving means on each roll; a main power drive; means connected with the driving means, one for each roll, for varying the rotational speed of the driving means for the rolls; a member connecting each of the last mentioned means and the main driving means; each of said members including coacting elements providing slippage between the rotational speed varying means and the main power drive in response to the relative speed difference between the rolls and their driving means on the respective sides of the work station; a differential speed driving means connected to the main power drive and each of the rotational speed varying means and actuated by the differential speed between the main power drive and each of the rotational speed varying means, whereby to compensate for the variance in rotational speed in the driving means; and means connected with one of the rotational speed varying means and one of the coacting elements of one member adapted for automatically regulating the tightness of the roll of web wrapped on the winding roll.

9. A device of the class described comprising a supporting stand; a reel mounted on the stand to revolve periodically to predetermined working positions and there to remain fixed for a certain period; a pair of rolls journalled on the reel in

spaced relation to each other, a work station; a continuous web adapted for winding on one roll as it is unwound from the other roll and having a portion intermediate the rolls operated on under constant tension at the work station; a driving means on each roll; a main power drive; means connected with the driving means, one for each roll, for varying the rotational speed of the driving means for the rolls; a member connecting each of the last mentioned means and the main driving means; each of said members including coacting elements providing slippage between the rotational speed varying means and the main power drive in response to the relative speed difference between the rolls and their driving means on the respective sides of the work station; a differential speed driving means connected to the main power drive and each of the rotational speed varying means and actuated by the differential speed between the main power drive and each of the rotational speed varying means, whereby to compensate for the variance in the driving means; and a detachable means between each of the driving means and each of the rotational speed varying means to permit removal of the rolls for replacement without disturbing the position of the rotational speed varying means.

10. A device of the class described comprising a supporting stand; a reel mounted on the stand to revolve periodically to predetermined working positions and there to remain fixed for a certain period; a pair of rolls journalled on the reel in spaced relation to each other, a work station; a continuous web adapted for winding on one roll as it is unwound from the other roll and having a portion intermediate the rolls operated on under constant tension at the work station; a driving means on each roll; a main power drive; means connected with the driving means, one for each roll, for varying the rotational speed of the driving means for the rolls; a member connecting each of the last mentioned means and the main driving means; each of said members including coacting elements providing slippage between the rotational speed varying means and the main power drive in response to the relative speed difference between the rolls and their driving means on the respective sides of the work station; a differential speed driving means con-

nected to the main power drive and each of the rotational speed varying means and actuated by the differential speed between the main power drive and each of the rotational speed varying means, whereby to compensate for the variance in rotational speed in the driving means; and means on the reel for journalling a third roll thereon so as to provide a replacement for the reel unwound.

11. In a device of the class described comprising a pair of rolls, a continuous web being wound on one roll and unwound from the other and passing therebetween, a driving means on each roll, a main power drive, means connected with the driving means on each roll for varying the rotation speed of the driving means for the rolls, a member connecting each of the last mentioned means and the main power drive, each of said members including coacting elements providing slippage between the rotational speed varying means and the main power drive in response to the relative speed difference between the rolls and their driving means, and a differential speed driving means connected to the main power drive and each of the rotational speed varying means and actuated by the differential speed between the main power drive and the respective first mentioned means whereby to compensate for the variance in the rotational speed in the driving means.

12. The combination with a reel for supporting a pair of rolls from one of which a web is wound on the other and between which the web is being worked upon under constant tension of a power drive for the rolls; means connecting the power drive with each of the rolls; each of said means including a unit for varying the rotational speed of the drive for the respective rolls, and also coacting elements effective upon a variation in the relative speed between the rolls and their respective power drives on opposite sides of the work to produce a slippage between the power drive and each roll; and a control unit including a differential speed driving means connecting the power drive with each of the units for controlling the operation of the rotational speed varying units.

CHARLES S. CAFFREY.
